US0D1064787S

(12) **United States Design Patent** (10) Patent No.: **US D1,064,787 S**
(45) Date of Patent: ** Mar. 4, 2025

(54) **LOCK**

(71) Applicant: **Ningbo Eudemon Child Protective Equipment Co., Ltd.**, Ningbo Zhejiang (CN)

(72) Inventors: **Binhui Li**, Zhejiang (CN); **Yingfeng Chen**, Zhejiang (CN)

(73) Assignee: **Ningbo Eudemon Child Protective Equipment Co., Ltd.**, Ningbo Zhejiang (CN)

(**) Term: **15 Years**

(21) Appl. No.: **29/911,278**

(22) Filed: **Aug. 31, 2023**

Related U.S. Application Data

(62) Division of application No. 35/515,592, filed on Nov. 3, 2022 (U.S. filing date under 35 U.S.C. 384), and having an international filing date of Nov. 3, 2022, now Pat. No. Des. 1,034,147.
